METHOD OF MAKING PAVING MATERIAL

Application filed September 28, 1929. Serial No. 395,813.

The present invention relates to methods of or processes for mixing and drying materials suitable for the formation of layers or courses of roads or other pavements, and 5 more particularly to the methods of making road making materials wherein a mineral aggregate of stone or pebble or sand or "fines" or a mixture thereof is coated with a bituminous or similar binding material, and 10 particularly adapted to be laid hot or cold, and compacted to form a permanent course or layer of the roadway.

The objects of the present invention are to provide a method of coating a mineral 15 aggregate suitable for the aggregate of bituminous roadways, at the quarry or gravel pit whence the aggregate is obtained, in order to make necessary but a single handling of the aggregate to produce a road material 20 of aggregate coated with a bituminous or similar binder, which material can be stored until wanted for placement, without forming an agglomerate, or which may be loaded, directly it is made, into railway cars or motor trucks for transportation to the place 25 where it is to be used in road construction.

A further object of the invention is to provide a process in which relatively low grade oils, such as crude oil or fuel oil or 30 bunker oil are used as the binding and coating material, for mineral aggregates, such materials being usually sufficiently fluid, when hot, to obviate the use of a liquefier, and being applied usually to a hot aggregate.

35 Another object of the invention is to provide for the continuous treatment of an aggregate at the sand pit or quarry where a continuous stream of mineral aggregate is first subjected to heat in a current of hot 40 air to dry the aggregate and remove the dust therefrom, said stream being thereafter subjected to a continuous agitation or mixing process and treated first to a waterproofing material in liquid form and thereafter being treated with a hot bituminous binding

material which has a relatively small asphaltic content, all under agitation, until the particles of mineral aggregate are completely covered with said binding material.

A further object of the invention is to 50 provide a method of producing a coated aggregate highly useful in the building of roads, particularly adapted for moderate or light traffic at an extremely low cost and in large quantities and to utilize whatever 55 stone may be available within economic proximity to the road being built and by economic proximity, we mean so near the building operation that the haulage thereto by a train or truck is not excessive or prohibitive.

A further object of the invention is to effect, in a single continuous and progressive treatment, the drying, dusting, waterproofing and coating with a suitable binding 65 material, mineral aggregate suitable for the construction of roadways or other pavements, and at the same time to substantially increase the ductility of said binding material.

A further object of the invention is to 70 provide a paving material which will require the use of a minimum amount of binding material thereby providing a substantially non-skid surface of the roadway.

A further object of the invention is to 75 provide a method whereby local stone, which may not be of the highest character, and even stones that are water-absorptive and relatively low in strength may be utilized, by subjecting the stone to a temperature sufficient to evaporate the water in a stream of warm air and to thereafter impregnate the stone with a coating material which at atmospheric temperatures has viscosity and cohesiveness sufficient to firmly bind together the aggregate of a roadway and which is highly resistant to the wear of traffic, and to water.

A further object is to provide a simple easily practiced process for continuously drying, waterproofing (when necessary or desirable) and coating with liquid asphalt or similar material a constantly progressing or flowing stream of mineral aggregate.

Further objects of the invention will appear in the specification and claims below.

Although the process or method of making a paving material forming this invention may be performed in a variety of ways or even by hand operations, Donald McKnight Hepburn, one of the present inventors has also invented an apparatus particularly adapted for the automatic practice of this improved process, said apparatus forming the subject-matter of a co-pending application, filed by him August 10, 1929, Serial No. 384,998, and for the purpose of making clear the nature of the treatment to which the aggregate is subjected, and how the process may be performed commercially, but without limiting the practice of the process thereto, said apparatus is illustrated in the drawings forming a part of this application, to which reference will now be made.

Fig. 1 is a side elevational view, partly in section, of the essential parts of a combined drying, dusting, heating, waterproofing and mixing machine, showing the mode of introducing the aggregate thereinto, of causing it to traverse the length thereof substantially in a continuous stream, and the manner of supplying fuel to the heater and waterproofing and coating material continuously to the aggregate, together with the mode of continuously introducing into the mixing portion of the apparatus, "fines", sand and/or chemicals, such as sulphur, for the purpose of increasing the viscosity of the binding material and to increase the thickness of the coating.

Fig. 2 is a transverse cross-sectional view, on the line 2—2 of Fig. 1.

Fig. 3 is a transverse cross-sectional view looking in the opposite direction to that in Fig. 2 and taken on the line 3—3 of Fig. 1, and

Fig. 4 is a transverse cross-sectional view on the line 4—4 of Fig. 1.

The rotatable cylinder 1 is preferably composed of three aligned sections, the upper section 1^a comprising a heating chamber wherein the mineral aggregate is heated, dried and freed from dust; an intermediate section 1^b wherein the aggregate is cooled and wherein the aggregate may be sprinkled with any suitable liquid, such as kerosene, rubber in solution or soap solution and is herein termed the cooling and water-proofing section or chamber; and a mixing chamber 1^c wherein hot binding material is added to the aggregate and the aggregate is continuously stirred and agitated for the purpose of thoroughly coating each piece of the aggregate

with the binding material, and is herein termed the mixer section or chamber 1^c.

The adjacent ends of the heating chamber 1^a and of the intermediate section 1^b are preferably spaced from each other and the gap therebetween is closed by a split ring 2, tightly fitting over the said adjacent ends of said chambers and firmly clamped thereon by bolts 3 passing through the radial flanges 4 thereof. The adjacent ends of the waterproofing chamber 1^b and the mixing chamber 1^c are similarly spaced apart and the gap therebetween is closed by a like split ring 2', with flanges 4' and bolts 3' passing therethrough.

The rotatable cylinder 1 is preferably supported on a series of pairs of anti-friction rollers 5—5, and the cylinder 1 is provided with a plurality of circular tracks 2, one for each pair of rollers. The lower end of the mixer section 1^c preferably fits loosely within a circular opening 7 through a side wall of a stationary housing 8 which is in communication with a centrifugal fan 9 arranged to impel a strong blast of air (at substantially atmospheric temperature in all but the section 1^a) through the entire length of the rotatable cylinder 1.

The housing 8 is also provided with a chute 10 adjacent the lower end of the mixer section 1^c through which the material coming thereto from the lower end of the mixing chamber 1^c is delivered to a conveyor for storage or to a truck or car for transportation. Adjacent the upper end of the rotatable cylinder 1 is a bucket elevator 11 adapted to discharge its load into a hopper 12 having a chute 13 extending into the upper and otherwise open end of the heating section 1^a. Near the upper end of the heater section 1^a is a toothed wheel or sprocket wheel 14 upon which runs a sprocket chain 15 connected to any suitable source of power for continuously rotating the cylinder 1. Within its upper end, the intermediate section 1^b is provided with a spider 16 rigidly secured thereto and provided at its center with two rings 17 concentric with the axis of the cylinder, and fitting against the marginal edges of the opposite sides of a disk 18.

Within the cylinder 1 and extending practically axially thereof from the lower end thereof to the upper end of the intermediate section 1^b is a series of pipes, the lower ends of which may be and preferably are within the stationary housing 8 and extend through the lower wall thereof. Extending through the disk 18 is the fuel pipe 19, the upper end of which is provided with a burner 20 projecting forwardly substantially axially of and at the lower end of the heating chamber 1^a. This fuel pipe 19 is provided with a valve 21 by means of which the flow of fuel oil to the burner may be regulated and controlled. Extending substantially parallel to the fuel

pipe 19 is a pipe 22 by means of which air under substantial pressure is conducted to the burner to aid in the combustion of the fuel. This air pipe 22, also extending through the lower wall of the housing 8 is preferably provided with a controlling valve 23. When fuel is admitted through the pipe 19 to the burner 20 and ignited and supplied with air from the air pipe 22 and from the fan 9, a hot flare flame or blast is projected forwardly from the burner 20 and substantially fills the chamber 1^c.

Also passing through the disk 18 is a pipe 24 extending into the housing 8 and thence downwardly through the lower wall of the housing 8 where it is provided with a controlling valve 25. The upper end of this pipe 24 is provided with a series of perforations 26 through which any suitable liquid may be sprayed onto the stream of aggregate delivered thereto from the heating chamber 1^a, as will be referred to again below.

The fourth pipe 27 of the group of pipes or tubes is preferably well above the bottom of the cylinder 1 and may terminate at its upper end short of the disk 18. In the drawings, the upper end of said pipe 27 is shown as suspended by a hanger or clamp 28 from the pipe 24 and terminating at the point where the perforations 26 in the pipe 24 begin. Said tube or pipe 27, after extending into the housing 8 and thence downwardly through the bottom thereof is also preferably provided with a hand operated valve 29. It is through this pipe 27 that the coating and binding material for the aggregate is conducted into the mixing chamber 1^c and discharged through the perforations upon the aggregate under agitation therein. Within the forward part of the housing 16 is a strut or bracket 31 in which the pipes 19, 22, 24 and 27 are rigidly mounted and held together. Thus the group of pipes is rigidly supported substantially axially of the cylinder 1 in the spider 16 and bracket 31, and the spider is free to rotate around the stationary disk 18 when the cylinder 1 is rotated.

The heating chamber 1^a is preferably provided on the inner surface thereof with a series of troughs 32 preferably disposed parallel to the axis of the cylinder. When the cylinder is rotated in the direction of the arrow 33 (Fig. 2) these lifting troughs fill with aggregate and lift it to a point near the top of the cylinder whence it falls back to the bottom side of the cylinder and transversely through the flame from the burner 20 and transversely through the blast of air coming from the fan 9 and heated by said flame.

The interior surface of the mixer section or chamber 1^c is provided with a plurality of series of stirrer blades 34, the blades of each series being preferably disposed in a circle on the interior of the section 1^c, and inclined at substantially 45° to the direction

of their rotative path. Were the inner surface of the section 1^c to be laid out flat, in development, the blades in any series would be parallel to each other, and those of the adjacent series would be parallel to each other and would make angles of 90° with the blades in the series first above mentioned. These series of rings of stirrer blades 34 preferably extend for substantially the full length of the mixing section 1^c.

Within the cylinder 1, and over the pipes 19, 22, 24 and 27, is preferably mounted a guard plate or shield or roof 35 of sheet metal supported on any of the said pipes and the walls of which diverge sharply downwardly so that any of the coated stones which may stick to the stirrer blades 34 and drop therefrom when the blades are in their highest position during the rotation of the cylinder, and strike said roof, will not adhere thereto or accumulate thereon.

On the housing 8 is preferably mounted a hopper 36, the bottom of which is preferably provided with a feed screw 37 for the purpose of delivering steadily from the hopper 36 any fine solid materials which are needed or desired in the mixture under treatment in the mixing chamber 1^c. The feed end of the screw 37 communicates with a chute 38 extending downwardly therefrom into the lower end of the mixer chamber 1^c and well above the lowest portion of the cylinder section 1^c, so that it is clear of the stream of material under treatment in said section 1^c.

In carrying out the improved process of this application with the apparatus above described, the fuel oil from the fuel pipe 19 is ignited at the burner 20 and air under pressure is supplied through the air pipe 22. The fan 9 impels a blast of air at atmospheric temperature through the mixer section 1^c and the intermediate section 1^b but the air upon entering the heater chamber 1^a is highly heated by the flame from the burner 20. The cylinder 1 is constantly rotated by the chain 15 driving the sprocket wheel 14.

The aggregate in form of stone or sand or gravel as it comes from the quarry, crusher or pit is continuously dropped from the elevator 11 into the hopper 12 and thence is delivered to the heating chamber 1^a. By the rotation of the cylinder the aggregate is continuously lifted up one side of the heating chamber 1^a by the troughs 32 until it reaches a point near the top of the cylinder whence it is spilled out or dropped from the said troughs or lifters and falls transversely through the flame and through the current of air to the bottom of the chamber 1^a. This lifting and dropping of the aggregate in this blast of hot air in the first part or portion of its travel through its path in the cylinder performs two functions, (1) the aggregate is heated to a temperature sufficient to evaporate the water contained therein, and

(2) any dust mixed with the aggregate is blown away and the aggregate is thereby cleaned. The inclination of the axis of the rotating cylinder 1 effects, by gravity, slow progression or travel of the aggregate through its path in the cylinder in a direction contrary to that of the blast of air supplied thereto from the fan 9. The aggregate thus progresses by gravity to the lower 10 end of the heater section and except in the heating section 1^a where a part of it is "raining" through the flame and blast of air, it flows as a stream over the split ring 2 and between the spokes or arms of the spider 16 15 into and through the second portion of its path which is through the intermediate section 1^b and over the second smooth split ring 2'. Immediately after the aggregate passes the burner 20 it meets the cool air impelled 20 through the sections 1^c and 1^b from the fan 9 and moves in a direction contrary thereto. Thus the heated aggregate and the coating, after its application thereto, are also substantially cooled during their travel through 25 the section 1^c.

When the material with which the aggregate is to be coated is too thick and viscous even when heated to be easily mixed with the aggregate or to evenly coat the same, to the 30 aggregate in the second stage or portion of its travel in its path through the cylinder is added a liquefier of the bituminous material with which the aggregate is to be coated, such as kerosene or naphtha or any other 35 liquefier which may also contain other ingredients. Such liquefiers or mixtures or solutions are conveyed to the intermediate section 1^b through the pipe 24 and are sprayed or otherwise discharge onto the aggregate 40 therein and flowing therethrough by gravity, through the perforations 26 at the upper end of the pipe. Such liquids, when used, are ordinarily at atmospheric temperatures, and hence also contribute to the rapid cooling of 45 the aggregate coming from the chamber 1^a.

Having thus been cooled in its travel between the drying or heating chamber 1^a and the mixing chamber 1^c, the stream of aggregate enters the third or last portion of its 50 path by flowing into the upper end of the mixer or chamber 1^c. Immediately upon leaving the intermediate section 1^b the aggregate passes under the upper end of the spray or jet pipe 27 which is supplied with a liquid 55 binding material preferably heated to the proper temperature dependent upon the character of the binder used, and thereafter throughout its travel through the cylinder 1^c a suitable quantity of coating material is 60 continuously sprayed upon the aggregate in the mixer chamber 1^c. As soon as the stream of aggregate meets the stirrer blades 34 it is lifted higher on the side of the rotating section 1^c than it was in traversing the smooth 65 surfaces of the intermediate section 1^b and of

the split rings 2—2'. On the side of the cylinder 1^c it slides from one stirrer blade to a stirrer blade in the next concentric ring of stirrer blades, working back and forth from one blade to the next and at the same 70 time slowly progressing by gravity through the length of the mixing chamber 1^c until it reaches the lower end thereof.

Shortly prior to the time when the mixing and coating of the aggregate has been completed in the mixer section 1^c, a relatively small quantity of "fines" or sand, either alone or mixed with other materials, such as lime and/or sulphur, is added thereto for the purpose of obtaining a thicker coating on the individual pieces of aggregate, a more even distribution of the coating material on the individual pieces, and imparting toughness or hardness or increased viscosity and cohesion to the binding material. The fine material is continuously added to the aggregate flowing through the last stage or portion of its travel or path through the cylinder 1, being fed from the hopper 36 by the screw 37 and delivered to the aggregate in the mixing 80 section 1^c as a continuous stream running down through the end of the chute 38. The blast from the fan 9 will prevent the material from being deposited directly below the lower end of the chute 38, because it is finely 85 comminuted and dust-like. These small particles so added will be blown by the blast of air some way upwardly toward the upper end of the mixing chamber 1^c before it comes to rest on the aggregate being agitated therein, particularly if the lower end of the chute 38 be spaced a substantial distance above the upper surface of the aggregate under treatment in the mixing chamber 1^c.

When the coated aggregate leaves the lower end of the mixer section 1^c it falls into the chute 10 and thence is carried away for storage by a continuous conveyer, or is delivered into cars or trucks for transportation to the place where the roadway is being made.

Thus is provided a process or method of continuously treating a mineral aggregate by forming it into a stream and moving it continuously by gravity through a predetermined path in a direction opposite to that of a blast of air driven thereover, and by subjecting the aggregate during the first portion of its travel to a drying and dusting action in a flame and in a hot blast of air to evaporate the water contained therein therefrom and then continuously delivering said aggregate as a moving stream to a mixing chamber wherein there is continuously added coating material while the aggregate is kept under constant agitation, and finally, shortly prior to the time when said aggregate travels through the last portion or stage of its path and at a time too late in the mixing operation to permit of the formation into balls or masses of aggregate, adding "fines" and/or

sulphur and/or other dry materials which increase the thickness of the coating and renders the bituminous material better suited for road making purposes.

5 In making a paving material designed to be laid cold and compacted of the type known in the trade as "Amiesite", the aggregate for a course of the road which is delivered from the elevator 11 to the upper end of the cylinder 1 is a graded aggregate. The heat to which it is subjected in the drying and heating section 1^a is sufficient to evaporate any water contained therein, but the aggregate itself is not heated to such a degree that in 10 the intermediate section 1^b its temperature may not be readily reduced by the cool air blowing thereover to at or about 90° F. In passing through the intermediate section or portion of its path, a liquefier, such as kerosene or other slightly volatile oils alone or 15 admixed with other ingredients is sprayed thereon continuously through the perforations 25 in the liquefier pipe 24, the quantity being substantially from one to one and a half 20 gallons for each ton of aggregate passing therethrough.

When the aggregate flows from the intermediate section or portion of its path into the final portion of its course, it flows under 25 the pipe 27 and substantially so long as the material is passing through said chamber, asphalt having a penetration at atmospheric temperatures of from 70 to 100, but heated to a temperature of from 250 to 300° F. is 30 delivered to the aggregate in the mixing chamber and for substantially the entire time that the aggregate is flowing through said section 1^c. At the same time the aggregate is subjected to a vigorous agitation due 35 to the rotation of the cylinder and the action of the blades 34. The quantity of asphalt delivered to a ton of aggregate passing a given point within the chamber will vary considerably, depending upon the size of the aggregate and the quality of the asphalt, but generally, for a ton of aggregate which will pass through a quarter inch mesh screen, the quantity of asphalt is from 80 to 100 pounds or 4 to 6% or 7% of the weight 40 of the aggregate. As the aggregate flows to a point near the end of its path of travel, sands or "fines," from 5 to 10% of the weight of the aggregate, are continuously delivered to the aggregate under treatment 45 in the mixing chamber and is at a point sufficiently far up into the chamber to insure the thorough mixing thereof with the aggregate as it is acted upon by the blades at the lower end of the mixing chamber 1^c. The 50 aggregate thus coated and prepared falls through the chute 18 as a completely coated aggregate ready for placement or storage.

This process is also applicable to the making of a paving material which is to be laid hot, and wherein an asphaltic material hav-

ing a penetration index of 50, for instance, at atmospheric temperatures, is used. In making this type of paving, the aggregate is heated to temperatures which are considerably higher than those used in making the cold laid pavement above described, and it is preferable to heat the asphaltic cement to be applied thereto to a temperature of from 350 to 400° F. As soon as the coating is completed, the material should be placed upon the roadway and compacted hot for if the coated aggregate were allowed to cool before placement, the pieces of aggregate would rigidly cohere to each other and would require re-heating for placement upon the road.

The process is also applicable to the use of binding and coating materials, the base of which is a cheap low grade oil, such as fuel oil, bunker oil, sludge or waste products from refining processes and in which very little asphaltic material remains. Such binding materials comprise a cheap low grade oil combined at relatively high temperatures with sulphur, (e. g. 6% of the weight of the oil) and preferably one or more of the metallic salts of the fatty acids (as for example, aluminum stearate, 1/2 of 1% of the weight of the oil).

A paving cement of this character once compounded behaves like and in fact greatly resembles the asphalts used in road making. At 250° to 300° F. it is very fluid and may be used in the process above described as a substitute for the asphalt. At atmospheric temperatures, its coherence, ductility, hardness and toughness compare very favorably with the asphalts ordinarily used in road construction.

But in using these materials as binders, in this process a liquefier is usually unnecessary, and it is preferable that the aggregate be heated to such a temperature that at the time it reaches the lower end of the mixing chamber its temperature shall be a little higher than that of the binding material discharged thereon from the fuel feed pipe 27. The cooling of the aggregate by the current of air between the upper end of the intermediate section 1^b and the lower end of the mixing section 1^c should therefore be avoided or reduced as much as possible by reducing the volume of the air discharged over the stream of aggregate to the minimum required for removing the moisture and dust from the aggregate, or by heating the air prior to its delivery to the fan, or prior to its discharge from the fan into the lower end of the section 1^c.

Having thus described our invention, what we claim and desire to protect by Letters Patent of the United States is:

1. The method of continuously making a bituminous paving material, which consists in causing a substantially continuous stream

- of mineral aggregate to flow gravitationally slowly through a predetermined path, and continuously impelling a strong current of air from the atmosphere over and parallel to said stream throughout the length of said path and in a direction opposite to that of said stream of aggregate, heating said current of air in its flow over the first portion of said path of said aggregate and vigorously agitating said aggregate in said first portion of said path in said current of hot air to heat and dry said aggregate and separate dust therefrom, reducing the temperature of the heated aggregate in its flow 10 through the remainder by said path of said current of air flowing thereover and transferring by said current of air the heat of said cooling aggregate to the aggregate then in said first portion of said path, and continuously discharging hot bituminous binding material over and continuously agitating said stream of aggregate during its travel through said last portion of its path.
2. The method of continuously making a bituminous paving material, which consists in causing a substantially continuous stream of mineral aggregate to flow gravitationally slowly through a predetermined path, and continuously impelling a strong current of air from the atmosphere over and parallel to said stream throughout the length of said path and in a direction opposite to that of said stream of aggregate, heating said current of air in its flow over the first portion of said path of said aggregate, and continuously lifting and dropping said aggregate in said first portion of said path through said current of hot air to heat and dry said aggregate and separate dust therefrom, reducing the temperature of the heated aggregate in its flow 20 through the remainder of said path of said current of air flowing thereover and transferring by said current of air the heat of said cooling aggregate to the aggregate then in said first portion of said path, and continuously discharging hot bituminous binding material over and continually agitating said stream of aggregate during its travel through said last portion of its path.
3. The method of continuously making a bituminous paving material, which consists in causing a substantially continuous stream of mineral aggregate to flow gravitationally slowly through a predetermined path, and continuously impelling a strong current of air from the atmosphere over and parallel to said stream throughout the length of said path and in a direction opposite to that of said stream of aggregate, heating said current of air in its flow over the first portion of said path of said aggregate and vigorously agitating said aggregate in said first portion of said path in said current of hot air to heat and dry said aggregate and separate dust therefrom, reducing the temperature of the heated aggregate in its flow 30 through the remainder of said path of said current of air flowing thereover and transferring by said current of air the heat of said cooling aggregate to the aggregate then in said first portion of said path, and continuously discharging hot bituminous binding material over and continually agitating said stream of aggregate during its travel through said last portion of its path.
4. The method of making a bituminous paving material which consists in causing a substantially continuous stream of mineral aggregate to flow gravitationally slowly through a predetermined path and continuously impelling a strong current of air from the atmosphere over and parallel to said stream throughout the length of said path and in a direction opposite to that of said stream of aggregate, heating said current of air in its flow over the first portion of said path of said aggregate and vigorously agitating said aggregate in said first portion of said path in said current of hot air to heat and dry the aggregate and to separate dust therefrom, reducing the temperature of the hot aggregate in its flow through the remainder of its said path by said current of air flowing thereover and transferring by said current of air the heat of said cooling aggregate to the aggregate then in said first portion of said path, and continuously delivering to said stream of aggregate, shortly before said aggregate reaches the end of said path, a relatively small quantity of finely divided mineral matter.
5. The method of making a bituminous paving material, which consists in causing a substantially continuous stream of mineral aggregate to flow gravitationally slowly through a predetermined path and continuously impelling a strong current of air from the atmosphere over and parallel to said stream throughout the length of said path and in a direction opposite to that of said stream of aggregate, heating said current of air in its flow over the first portion of said path of said aggregate and vigorously agitating said aggregate in said first portion of said path in said current of hot air to heat and dry the aggregate and to separate dust therefrom, reducing the temperature of the hot aggregate in its flow through the remainder of its said path by said current of air flowing thereover and transferring by said current of air the heat of said cooling aggregate to the aggregate then in said first portion of said path, and continuously discharging a liquid liquefier on said aggregate as it travels through the intermediate portion of its path, and continuously discharging hot bituminous binding material over and continually agitating said stream of aggregate during its travel through the last portion of its path.
6. The method of making a bituminous paving material, which consists in causing a substantially continuous stream of mineral aggregate to flow gravitationally slowly through a predetermined path and continuously impelling a strong current of air from the atmosphere over and parallel to said stream throughout the length of said path and in a direction opposite to that of said stream of aggregate, heating said current of air in its flow over the first portion of said path of said aggregate and vigorously agitating said aggregate in said first portion of said path in said current of hot air to heat and dry the aggregate and to separate dust therefrom, reducing the temperature of the hot aggregate in its flow through the remainder of its said path by said current of air flowing thereover and transferring by said current of air the heat of said cooling aggregate to the aggregate then in said first portion of said path, and continuously discharging a liquid liquefier on said aggregate as it travels through the intermediate portion of its path.

- mediate portion of its path, continuously discharging hot bituminous binding material over and continuously agitating said stream of aggregate during its travel through the last portion of its path, and continuously delivering to said stream of aggregate, shortly before said aggregate reaches the end of said path, a relatively small quantity of finely divided material.
6. The method of continuously making a paving material which consists in causing a substantially continuous stream of mineral aggregate to flow gravitationally slowly through a path and continually impelling a current of air over and parallel to said stream in a direction opposite to that of said stream of aggregate, heating and thoroughly agitating said aggregate during its travel through the first portion or stage of its said path to dry said aggregate and to remove dust therefrom and continuously discharging on said aggregate during the latter portion or stage of its said path a hot fuel-oil binding composition which is freely fluid when hot and which is of asphaltic consistency at atmospheric temperatures, and thoroughly agitating and mixing said aggregate therewith during the said latter portion or stage of said path.
7. The method of continuously making a paving material which consists in causing a substantially continuous stream of mineral aggregate to flow gravitationally slowly through a path and continually impelling a current of air over and parallel to said stream in a direction opposite to that of said stream of aggregate, heating and thoroughly agitating said aggregate during its travel through the first portion or stage of its said path to dry said aggregate and to remove dust therefrom and continuously discharging on said aggregate during the latter portion or stage of its said path a hot fuel-oil binding composition which is freely fluid when hot and which is of asphaltic consistency at atmospheric temperatures, and thoroughly agitating and mixing said aggregate therewith during the said latter portion of said path, the temperature of said aggregate being preferably higher than that of said hot binding composition added thereto.
8. The method of continuously making a bituminous paving material, which consists in causing a substantially continuous stream of mineral aggregate to flow slowly through a predetermined path, and continuously impelling a strong current of air from the atmosphere over and parallel to said stream throughout the length of said path, heating said current of air in its flow over the first portion of said path of said aggregate and vigorously agitating said aggregate in said first portion of said path in said current of hot air to heat and dry said aggregate and separate dust therefrom, reducing the temperature of the heated aggregate in its flow through the remainder of said path by said current of air flowing thereover, and continuously discharging hot bituminous binding material over and continuously agitating said stream of aggregate during its travel through said last portion of its path.
- In witness whereof, we have hereunto set our hands this 27th day of September, 1929.
